LEATHER TRIMMING MACHINE

Arthur W. Smith, Little Rock, Ark.

Application December 30, 1952, Serial No. 328,705

3 Claims. (Cl. 12—88)

1

This invention relates to a leather trimming machine and it consists in the combinations, constructions and arrangements of parts herein described and claimed.

Generally there is provided a leather trimming machine consisting of a base atop which is affixed a vertical standard upon the upper portion of which is mounted a motor having a drive shaft extending vertically upwardly therefrom. Upon the other side of the upper portion of the standard is a frame having mounted therein a vertical shaft atop which is a pulley which pulley is connected with the pulley on the drive shaft of the motor by means of a belt. The frame is equipped with reduction gears connected with the upper portion of the vertical shaft and with a drive gear at the lower end of the shaft. The drive gear at the lower end of the shaft connects with a bevel gear at the lower end of a driven shaft atop which is a circular cutting blade. Connected by means of a universal joint is a shaft emanating from the reduction gearing to further gearing which drives an angularly disposed shaft at the lower end of which is a feed wheel. The feed wheel is placed immediately adjacent the cutting knife and the apparatus is such that a shoe may be held with the plane of its sole in a vertical direction and trimmed in one operation by feeding the same and guiding the same to the feed wheel whereupon the sole will be trimmed in a neat and workmanlike manner.

It is accordingly an object of the invention to provide an apparatus of the character set forth which is comparatively simple in construction, relatively inexpensive to manufacture and yet effective and efficient in use.

Another object of the invention is to provide, in a device of the character set forth, a novel angularly disposed cutting and angularly disposed feed wheel both forming parts of the invention.

A still further object of the invention is to provide, in an apparatus of the character set forth, novel gearing forming a part of the invention.

Other and further objects of the invention will become apparent from a reading of the following specification taken in conjunction with the drawings, in which:

Figure 1 is a side elevational view of an embodiment of the invention,

Figure 2 is a plan view thereof,

Figure 3 is an enlarged fragmentary side elevational view similar to Figure 1 but showing certain elements of the invention in greater detail, and

2

Figure 4 is a fragmentary sectional view taken substantially along line 4—4 of Figure 3.

Referring more particularly to the drawings, there is shown therein a base 10 to which is affixed a vertically extending standard 11 having a reduced upper portion 12.

To one side of the portion 12 there is affixed by bolts 13 or the like a motor 14 having a vertically and upwardly extending drive shaft 15 provided with a pulley 16 at its upper end.

A frame generally designated at 17 is affixed to the other side of the portion 12 of the standard 11 by an interconnecting web plate 18. The frame 17 has connected to the upper side thereof in vertically spaced relation thereto by means of a plurality of bolts 20 or the like a horizontally extending plate 19. Vertically extending through plate 19 and the inner portion of the frame 17 is a shaft 21 having a pulley 22 mounted upon the upper portion thereof, which pulley is interconnected with the pulley 16 by means of an endless belt 23. A spacing collar 24 is interposed between the pulley 22 and the plate 19.

Affixed to the shaft 21 between the plate 19 and the upper end of the frame 17 is a relatively small gear 25 which is enmeshed with a relatively larger gear 26 which likewise lies between the plate 19 and the frame 17 and which is mounted upon a stub shaft 27 extending between the plate 19 and frame 17. A relatively small gear 28 is likewise mounted upon the shaft 27 and is enmeshed with a relatively large gear 29 mounted upon a shaft 30 which is revolvably mounted in the plate 19 and frame 17 and which extends downwardly to terminate in a universal joint 31 which connects the same with an angularly disposed shaft 32 which is journaled in an inwardly and downwardly extending arm 33 carried by a vertical arm 34 forming a part of the frame 17.

A gear 35 is affixed to the shaft 32 and is enmeshed with a gear 36 extending through a bearing 37 formed at the free end of the arm 33. The lower end of the shaft 38 which carries the gear 36 is provided with a feed wheel 39 having attached to the outer end thereof a guard plate 40. A block 41 is formed integrally upon the outer side of the lower portion of the frame 17 and has angularly and upwardly disposed therein a shaft 42 to the upper end of which is affixed a circular blade 43 and to the lower end of which is affixed a bevel gear 44 which is enmeshed with a gear 45 carried by the lower end of the shaft 21.

In operation, it will be apparent that when it is desired to trim, for example, a sole 46 which is attached to the welt 47 of a shoe generally des-

gnated at 48, it is only necessary to maintain the plane of the sole 46 in a vertical condition while at the same time manipulating the shoe 48 by hand so that the feed wheel 39 will maintain the same in proper contact with the knife 43 thus severing from the sole 46 the surplus portions thereof, as indicated at 49 in Figure 3. It will also be apparent that the reduction gearing 25, 26, 28, 29 will act to drive the shaft 30 and consequently the shaft 32, the gears 35 and 36 to thus revolve the shaft 38 and the feed wheel 39 at a much slower rate and in an opposite direction to the rate of speed of the knife 43 and the direction thereof.

While but one form of the invention has been shown and described herein, it will be readily apparent to those skilled in the art that many minor modifications may be made without departing from the spirit of the invention or the scope of the appended claims.

What is claimed is:

1. An apparatus of the character described comprising a base, a vertical standard mounted on said base, a motor mounted on one side of the top portion of said standard, a frame, a web

5

interconnecting the frame and the opposite side of said upper portion of the standard, a drive shaft extending vertically upwardly from said motor, a pulley at the upper end of said drive shaft, a vertical driven shaft carried by said frame, a pulley at the upper end of said driven shaft, a belt interconnecting the pulleys, feed wheel means carried by said frame, reduction gearing carried by said frame and driving said feed wheel means from said vertical driven shaft, and a rotary knife mounted on said frame and driven by said vertical driven shaft, said knife and said feed wheel means being adjacent each other.

10

2. An apparatus as defined in claim 1 wherein said knife is angularly disposed with respect to said feed wheel means.

20

3. An apparatus as defined in claim 2 wherein said feed wheel means is adapted to move at a speed relatively slower than the speed of said knife and wherein said wheel means and said knife are driven in opposite directions.
